COMBINED SERVING TRAY, BOWL AND COVER

James B. Swett, Barrington, R.I., and Sidney Z. Smith,
Worcester, Mass., assignors to Dart Industries Inc., a
corporation of Delaware

Filed Jan. 22, 1969, Ser. No. 15,439

Term of patent 14 years

Int. Cl. D7—01

U.S. Cl. D44—10

F / G. 1

FIG. 2

FIG. 3

FIG. 4

FIG. 5

FIG. 6

FIG. 1 is an exploded perspective view of a combined serving tray, bowl and cover, showing our new design;

FIG. 2 is a side elevational view with the cover omitted;

FIG. 3 is a bottom plan view;

FIG. 4 is an end elevational view with the cover omitted;

FIG. 5 is a bottom plan view of the bowl member; and

FIG. 6 is an enlarged scale partial sectional view on line 6-6 of FIG. 1.

We claim:

The ornamental design for a combined serving tray, bowl and cover, as shown and described.
